BOTTLE CAPPER

Rudolph Sonnenberg, Belvidere, Ill., assignor to
 Mid-West Bottle Cap Co., Belvidere, Ill., a corporation of Illinois

Application July 15, 1941, Serial No. 402,518

16 Claims. (Cl. 226—85)

This invention relates to capping machines of the type commonly employed for applying caps to milk bottles, and refers more particularly to a machine for assembling and seating a hood cap on a bottle.

The present invention is directed primarily to a capping machine for applying composite paper and metal hood caps to milk bottles, and to the combination thereof with a filling machine, though it will be understood that many phases of the invention are not limited to the application of metal hoods. Much difficulty has been experienced in the past in an effort to provide metal hood caps for milk bottles which would meet the necessary trade requirements. The most important obstacle to a satisfactory solution of the problem has been that of cost, both in the cost of the metal making up the cap, and the cost of equipment for making and applying the cap. I have found that both of these difficulties can be largely eliminated by partially pre-forming the cap of metal of very thin cross-section in such manner that the pre-formed hoods will withstand the usage necessitated by handling and shipment thereof, and by making a capping machine of such structure as to be capable of handling and applying the relatively delicate partially formed hood members. In this way I have been able to very materially reduce the amount of metal required in the hood. I am also enabled to eliminate the necessity for forming the hood member as a part of the capping operation as has been necessary in the past. This very greatly simplifies the operation of applying caps and greatly reduces the cost of the capping mechanism so that the use of metal hood caps is brought within the reach of small dairies which are financially unable to procure and operate the complicated forming and capping machines of the prior art.

An important part of this problem and the general object of the invention is the provision of a capping machine capable of handling the very thin section hoods and capable of applying these to a milk bottle without rupturing the hood during the handling and applying operations, and capable of seating the cap to produce a finished package of workmanlike appearance and sufficient rigidity to withstand the abuse occasioned by the handling of the bottles during delivery.

An important object of the invention is the provision of a capping device of generally improved structure which is more efficient in operation, more positive in its action, which is capable of seating caps of different design, and which is more compact and easy to operate.

A further object of the invention is the provision of hood applying mechanism and cap seating mechanism together with means for mutually supporting the mechanisms and coordinating their operations.

A still further object of the invention is the provision of hood applying and cap seating mechanisms coordinated for cooperative operation in a filler and capper to accommodate for bottles and caps of different sizes.

Another object of the invention is the provision of a novel and compact structure for locating a bottle in a capping position and seating a cap thereon.

10 A still further object of the invention is to provide a capper having improved cap seating means including means for seating the cap disk into the mouth of a bottle, and means for seating the skirt of a pre-formed metal hood around the neck of the bottle.

15 Another object is the provision of a novel form of capping head and a novel cap seating diaphragm of resilient material adapted to compress the skirt of a hood cap around the neck of the bottle.

20 A further object is the provision of a capper capable of seating either hood caps or conventional disk caps so that either may be selectively run in the machine without change of parts.

25 A still further object of the invention is the provision in a capper of novel means for centering and aligning the bottle with the cap seating means.

30 I have also aimed to provide novel means for controlling the flow of air from and to the cap seating diaphragm in timed relation with descent of the capping means.

35 Other objects and advantages will appear from the following description and the accompanying drawings, in which—

Figure 1 is a side elevation of a filling and capping machine embodying my invention;

Fig. 2 is a fragmentary side view of a cap seating mechanism embodying my invention with the capping head in the elevated position;

Fig. 3 is a vertical section through the cap seating mechanism with the parts in the position corresponding to Figure 2;

Fig. 4 is a vertical section through the cap seating mechanism with the parts in the disk seating position;

Fig. 5 is a section on the line 5—5 of Fig. 4 showing the diaphragm in contracted position;

Fig. 6 is a fragmentary face view of the diaphragm;

Fig. 7 is a longitudinal section through the diaphragm valve taken on the line 7—7 of Fig. 5;

Fig. 8 is a section similar to Fig. 7 with the parts in the position shown in Fig. 2;

Fig. 9 is a section on the line 9—9 of Fig. 2 showing the bottle centering and aligning means;

Fig. 10 is a fragmentary side view of the bottle centering and aligning means, and

Fig. 11 and 12 are sections similar to Figs. 4 and 5 showing another form of diaphragm.

The present invention is directed to a cap seating device adapted for use primarily in conjunction with the bottling of milk and similar dairy products, and while suitable for either hand or machine operation, is herein shown as embodied in a well known type of filling and capping machine, as will presently be more fully described, in which the milk bottles are automatically filled, transported through a hood applying position as indicated at 5 (Fig. 9) in which a hood member is loosely seated on the head of a bottle as shown in Figs. 1, 2 and 3, and the bottle is then moved to a cap seating position as indicated at 6 in Fig. 9. In this instance the cap seating device is supported on a pair of vertically disposed rods 12 and 13 attached to the frame of the filler and capper hereinafter described, by means of sleeves 14 and 15 interconnected by a transverse bar 17, the transverse bar and the sleeves being normally fixed with respect to the rod but movable thereon to adjust the machines to different sizes of bottles. The primary means for assembling the portions of the cap and completing the formation thereof directly on the head of the bottle are also carried on a reciprocating cross-head 18 having sleeves 19 and 21 on the rods 12 and 13. The crosshead 18 has a bearing member 22 (Figs. 3 and 4) through which an operating rod 23 passes, the rod having a collar 24 adapted to bear against the lower end of a bearing member 22, the collar being pinned to the operating rod. Means, presently to be described, is provided in the filler and capper for reciprocating the rod 23 in timed relation with other portions of the filler and capper and through a required operating stroke. A washer 25 seats against the upper side of the bearing member 22 and receives the end thrust of a spring 26 surrounding the rod, the washer being loose thereon. This spring functions as a safety device permitting movement of the operating rod independently of the crosshead in case the bottle is not properly placed under the capper, or something else limits the downward movement of the crosshead. The opposite end of the spring bears against a washer 27 on the operating rod which is pressed against a sleeve 28 having abutting relationship at its upper end against a crank 30 on the rod 23 and acting as a spacer.

It will be seen that the crosshead 18, the spring 26, and the sleeve 19, reciprocate together with the operating rod 23 and the collar 24 acts to support the crosshead and attached mechanism on the rod at the elevation required for the capping operation.

An inverted U-shaped yoke, indicated generally by the numeral 29, as best shown in Fig. 5, is attached to the crosshead 18 in spaced relation thereto by means of spaced blocks 31 (Fig. 3) and bolts or screws 32 and 33 (Fig. 5). At the upper end of the yoke is a bearing member 34 having a flange 35 seated against the underside of the yoke, the bearing member being held in position by a removable pin 36. Passing through this bearing member is a stem 37 carrying a plunger 38 at its lower end and a collar 39 at its upper end. A spring 41 is positioned on the stem 37, one end thereof bearing against the bearing member 34 and the opposite end bearing against a collar 43 pinned to the stem, the spring normally urging the stem downward. This movement is limited by contact of the collar 39 against the bearing member 34. The lower end of the yoke 29 carries inwardly disposed ribs 44 and 45 seated in ways 46 and 47 of a head

support, indicated generally by the numeral 48 provided with a central guide opening 49 through which the stem 37 passes, a suitable sleeve bearing 51 being provided therebetween. The guide opening also serves to provide at its upper end an abutment for contact with the collar 43 for a purpose presently to be described. The head support has a cylinder designated generally by the numeral 52 shaped and positioned for the reception of a tube 53 carrying the conventional cap disks as indicated at 54, the tube 53 and cylinder 52 forming a cap disk magazine. The support 48 has a laterally disposed way 55 along which reciprocates a shuttle 56 which passes under the stack of caps 54 to slice a disk from the bottom of the stack into a plunger chamber 57, as shown in Fig. 3, within which the plunger 38 reciprocates. The shuttle 56 is reciprocated by spaced links 58 on opposite sides of the way 55, the links being pivotally connected to levers 59, the levers being pivotally carried as shown at 61 on opposite sides of the cylinder 52. The levers 59 have arcuate slots as shown at 62 within which are received pins 63 carried on links 64 pivotally supported on ears 65 integral with the collar 43.

Depending from the head support 48 and concentric with the plunger chamber 57 is an internally threaded flange 66 within which is a central opening 67 communicating with the plunger chamber and in effect forming a part thereof, the walls of said opening converging slightly as best shown in Figs. 3, 4 and 5, the walls being stepped as they converge inwardly whereby to receive the cap disk 68 to retain the same in coaxial relationship and prevent its dropping through the opening until pressed therethrough by action of the plunger 38. Surrounding the opening 67 is a diaphragm seat indicated generally by the numeral 69 against which a ring portion 71 of a rubber or similar flexible diaphragm 72 is seated. The ring portion 71 is held against the seat by an upper clamping or spacer ring 73, seating within an annular shoulder 74 of the flange 66. The diaphragm 72 has a cup-like intermediate wall 75 terminating in an arcuate portion 76 at its lowermost point and continuing in an annular rim 77, the upper clamping ring 73 having an inner wall extending in spaced relation to the wall portion 75 and a bead 78 which projects downwardly into the interior of the arcuate portion 76. The annular rim 77 is clamped against the upper clamping ring 73 by a lower clamping ring 79 having an annular flange 81. The two clamping rings are compressed against the diaphragm by means of a screw threaded cap 82 having an inwardly disposed flange engaging against the flange of the lower clamping ring. The lower clamping ring has a ledge 83 projecting inwardly for partial support of the diaphragm when inflated and should come as close as conveniently possible to the outer surface of the bottle to lend maximum support to the diaphragm in this area. The diaphragm, best shown in Fig. 6, has a plurality of spaced ribs 84 extending radially on the arcuate portion 76 and on the inner or upper side thereof, which ribs provide additional support for the lower portion of the wall 75 and greatly increase the life of the diaphragm. These ribs provide additional stock to prevent the rubber from blowing out along the wall of the bottle whereas the thinner portions intermediate the ribs permit the diaphragm to contract in this area without producing ripples on the bottle contacting surface.

It will be seen that the skirt contracting mech-

anism is so constructed that by unscrewing the cap 82, the diaphragm and clamping rings can be quickly withdrawn from the flange for quick replacement of the diaphragm in case the same may be cut by broken bottles or for any other reason may be in need of replacement. Likewise, it may be easily removed for cleaning without dismantling the entire cap seating mechanism.

Figs. 3, 4 and 5 show successive steps in the operation of the cap seating mechanism. The bottles are successively moved into the position occupied by the bottle 85, the head of the bottle acquiring a hood 86 as it passes from the discharge station 5 to the cap seating station 6. Thereafter the hood seating mechanism moves downward under the action of the operating rod 23 from the position shown in Fig. 3 to the position shown in Fig. 4. During the first part of this movement the head support 48, the yoke 29 and the stem 37 and attached plunger 38 move downward as a body until an arcuate terminal portion 87 of the diaphragm contacts the hood at the rim of the bottle. The diaphragm 72 is preferably of rubber throughout but has a surface layer of canvas or similar material molded there-to in the area 87 to facilitate slippage of the hood during the capping operations. Upon continued downward movement of the crosshead 18 the diaphragm exercises a slight pressure against the hood, the major portion of the weight of the head support being counterbalanced by a spring 88 connected at one end to the head support cylinder 52, the opposite end thereof being connected to a rod 89 carried on the yoke 29 as shown at 91. The spring exerts an upward pull on the head support cylinder substantially equivalent to the weight thereof, whereby a minimum amount of pressure is exerted between the hood and the arcuate portion 87. Thus, this contact with the bottle holds the head support stationary while the plunger 38 moves downward in the plunger chamber 57, moving the disk 68 downward from the position shown in Fig. 3 to the position shown in Fig. 4, during which operation the disk is brought into contact with an annular shoulder 92 of the hood (Fig. 3). As the movement of the plunger continues, the disk bears this shoulder portion of the hood against the inner wall of the bottle as shown in Figs. 4 and 5, drawing the required stock from the mouth-spanning portion 93 of the hood. As the disk comes against the cap seat 94 of the bottle, the rim portion 95 of the hood is drawn tightly over the rim of the bottle against the slight resistance offered by the arcuate diaphragm portion 87, thus bringing the parts into the position shown in Fig. 4. During this downward movement of the head support, and while the diaphragm is passing down over the head of the bottle, the skirt 96 of the hood is gathered in slightly by contact with the diaphragm.

The crosshead 18 and yoke 29 continue their downward movement from the position shown in Fig. 4. Since the plunger 38 has reached the seated position with the cap against the cap seat 94, and the collar 42 has come into abutting relationship with the head support 48, continued downward movement of the yoke causes the spring 41 to be compressed and the resultant pressure applied to the head support 48, thus applying pressure between the arcuate diaphragm portion 87, the hood, and

the rim of the bottle. As this additional pressure is applied, the diaphragm is contracted around the head of the bottle as shown in Fig. 5 to close the pleats in the skirt of the hood and iron the metal of the hood into close conformity with the outer surface of the bead.

It will be seen that in conforming the diaphragm 72 to the outer surface of the bottle, it is necessary to reduce the size of the intermediate wall 75 below this normal size. This type of operation normally tends to cause the wall 75 to develop a series of ripples in its surface, and to avoid this occurrence, I provide the bead 78 and the transverse ribs 84. The operation of this structure is to cause the wall 75 to be stretched transversely of its length at the same time that it is being contracted inwardly, this stretching operation in one direction acting to shrink the wall portion in the circumferential direction and absorb the excess material between the ribs, thus preventing formation of ripples. This is particularly important when the diaphragm is used on light metal caps for the reason that such caps, being ductile and of low resiliency, tend to reproduce every minor imperfection in the diaphragm and thus the objectional wrinkles in the diaphragm will be reproduced as ribs or wrinkles in the skirt of the finished cap. The same phenomena occur when thin walled paper hoods are employed. A further function of the ribs is to reinforce the diaphragm in the unsupported areas between the bottle and the ledge 83. The required action is further facilitated by shaping the diaphragm so that the upper part or prominent portion 87 is brought directly into contact with the bottle and the wall gradually slopes away from the bottle, whereby the greatest amount of stretch is produced in that portion of the diaphragm which is most remote from the bottle, or in other words, the diaphragm is stretched most in those areas in which it must be contracted most.

Contraction of the diaphragm is caused to occur by admitting compressed air into the space between the upper clamping ring 13 and the inner surface of the diaphragm. The movement of air to and from the diaphragm is controlled by an air valve designated generally by the numeral 97 shown in section in its opposed positions in Figs. 7 and 8. Attached to the head support 48 at the flange 66 by means of screws 98 is a bracket 99 which projects upwardly and to the upper side of which is attached the air valve as indicated at 101. This valve includes a body 102 having an air inlet connected to a source of supply of compressed air by a conduit 103. The body has a central bore 104 extending longitudinally thereof and a lateral bore 105 intersecting with the bore 104. Positioned in the bore 104 on opposite sides of the bore 105 are valve seats 106 and 107, in this instance formed of brass, each having central bores 108 and 109 for the passage of air therethrough. Positioned in the lower end of the bore 104 beyond the valve seat 106 is a movable valve disk 111 of stainless steel in the form of a disk lapped to seat against the valve seat 106, as will presently be described. The body 102 also has a counterbore 112 into which is threaded a plug 113 having a central recess 114 carrying a spring 115 which acts against the valve disk 111 to urge it toward the seat 106. Communicating with the bore 104 below the seat 106 is a small bore 116 for admitting air from the inlet through the bore 108. Extending through the seat 106

and through the upper portion of the body 102 is a pin 117 longitudinally reciprocable and slightly longer than the bore within which it rides, the pin projecting into a chamber 118 formed in a cap 119 attached to the body 102 as by screws 121, which pass through the body 102 and engage the bracket 99 to secure the valve in position thereon. The angular position of the cap with respect to the body is determined by a locating pin 120. Positioned in the chamber 118 is a plunger 122 having a plunger rod 123 extending upwardly beyond the cap 119 and arranged when actuated downwardly to move the rod 117 to the position shown in Fig. 7, causing the end thereof to abut the valve disk 111 and unseat the same. The body is provided with a counterbore above the seat 107 which is internally threaded for the reception of a plug 124 which has an internal bore 125 of the same diameter as the bore 104 and forming a continuation thereof. Positioned in the bore 125 is a plunger 126 adapted to contact a valve disk 127 of stainless steel and having a lapped surface adapted to seat against the valve seat 107, the plunger having a rod 128 projecting upwardly beyond the upper end of the plug for actuation of the plunger to press the disk 127 against the seat. The plug is slotted as indicated at 129, the slots communicating with slots 131 on the inner side of the cap 119 to provide an air passage from the seat bore 109 past the disk 127 and through the slots 129 and 131 to the exterior of the valve. Communicating with the bore 105 is a conduit 132 which extends downwardly and through suitable fittings is attached to a boss 133 on the flange 66, which flange has a channel 134 which communicates with a channel 135 in the upper clamping ring 73, the junction between the clamping ring and the flange member being sealed by a small rubber gasket, as indicated at 136, seated in grooves extending annularly of the channels, the groove in the upper clamping ring being smaller than that in the flange so that upon removal of the gasket is retained with the ring. The upper clamping ring 73 also has a pin 137 engageable in an opening 138 in the flange member to locate the clamping ring in such manner as to bring the channels 134 and 135 into registration.

Attached to the rod 89 through a sleeve 139 and screws 141 is a guide member 142 (Figure 2), the guide member having parallelly disposed bores as indicated at 143, within which are received actuating plungers 144 and 145, the plungers being carried upon stems 146 and 147 having nuts 148 and 149 adapted to abut against the upper end of the guide member. Springs 151 surround the stems and normally urge the plungers downwardly into the position shown in Figure 2, and serve to permit of overtravel on the part of the plungers 144 and 145 in their downward movement, as will presently be described. The plungers 144 and 145 are spaced so that upon relative movement between the head support 48 and the yoke 29 the lower ends thereof come into contact with the plunger rods 123 and 128 of the valve, the relationship being such that the valve is thereby caused to be operated at the proper point in the relative movement between these two elements in order to cause the diaphragm to be contracted and in order to release the air from the diaphragm for return movement of the parts. In this instance the plunger 145 normally extends to a point somewhat closer to the plunger rod 128 than is the case with the plunger 144 and rod 123, thereby causing the plunger rod 128 and the plunger 126 to be de-

pressed slightly before the plunger 122. Thus in operation, upon relative movement between the head support 48 and the yoke 29, the plunger 145 engages the plunger rod 128 thereby moving the disk 127 against the seat 107 and closing the channel 109. Promptly thereafter the plunger 144 engages the plunger rod 123 causing the plunger 122 to move the rod 117 downwardly, thereby unseating the disk 111 against the action of the spring 115 and the air pressure within the bore, and permitting air to pass from the inlet 103 through the channel 116, the bores 108 and 105 and the conduit 132 to the space behind the diaphragm, causing the diaphragm to move to the position shown in Fig. 5. Upon relative return movement of the head support 48 and yoke 29 the plungers 144 and 145 move upwardly, the plunger 144 first permitting the plunger 122 to move upwardly and the disk 111 to seat under the action of the spring, thereby cutting off pressure to the diaphragm. Shortly thereafter the plunger 145 permits return movement of the stem 128 and opening movement of the disk 127 whereby the pressure of the air within the bore 105 is permitted to evacuate through the bore 109 and the slots 129 and 131, thus relieving the pressure within the diaphragm and permitting the same to return to the position shown in Fig. 3. It will be seen that the arrangement is such that there is substantially no unnecessary loss of air since the valve disk 111 is opened subsequent to the closing of the disk 127 and is closed prior to the opening thereof.

As the parts return to the position shown in Fig. 2, the counterbalancing mechanism, including the spring 28, tends to cause the head support 48 to follow upward and thus prevent operation of the shuttle 56 from feeding the next succeeding disk into the plunger chamber 57. In order to insure this operation, a rod 152 is provided, the lower end of which bears against the head support 48 as shown in Fig. 3 when the crosshead occupies its upper position, the rod being carried in a sleeve 153 fixedly attached to a bracket 154 on the upper end of an upright 155 attached to the sleeve 15 as shown in Fig. 9. The rod is of reduced diameter within the sleeve 153 to provide a shoulder as shown at 156 (Fig. 3). A spring 157 within the sleeve acts against the shoulder and thence against the inturned upper end 158 of the sleeve to normally urge the rod downward. The downward movement of the rod is limited by a pin 159 passing through the upper end of the rod. Because of the fixed position of the bracket 154 the rod 152 is brought into contact with the head support when the crosshead approaches its upper position, thereby urging the head support downward until the pins 63 reach the upper end of the slots 62 representing the limit of the inward feed movement of the shuttle 56.

Means are provided for centering and aligning successive bottles under the cap seating mechanism and are carried on the horizontal bar 17. This includes a vertically disposed arm 161 (Fig. 2) attached to the end of the bar 17 having a horizontally disposed portion 162 arranged to support spaced bearing spindles 163 and 164 (Figs. 9 and 10). Positioned on the inner ends of the spindles 163 and 164 are clamping arms 165 and 166 having depending portions 167 and 168 provided with hands 169 and 171 adapted to grip the neck of a bottle somewhat below the bead thereof, as best shown in Fig. 10. The arms 165 and 166 are geared together by gear

segments 172 to cause the arms to move in unison to grip the bottle and to bring the same to a uniform location and alignment. The arms are operated upon by a spring 173 which seats in sockets 174 and 175 at the upper ends thereof to urge the same outwardly and thus rotate the arms into contact with the bottle as shown in Fig. 10. The arm 165 carries an upwardly disposed lever 176 having a roller 177 at the remote end thereof, positioned for engagement by a slide 178 carried on a depending lever 179 attached to the crosshead 18 by means of bolts 181 in such manner that elevation of the crosshead brings the cam face 178 against the roller 177, thereby rotating the arms by the pins 163 and 164 from the position shown in Fig. 10 to the position shown in Fig. 2 so as to release the bottle. It will be seen that the bottle is gripped under spring pressure and consequently the bottles may vary to a substantial extent in the diameter of the neck without interfering with the operation of the bottle locating means. The arm 161 is attached to the connecting element 17 through a slotted opening 182 in the arm and a cap screw 183 passing therethrough and into the element 17, which act to secure the parts in position in any desired adjusted elevational position, the element 17 and the arm being mutually shaped to prevent tilting movement of the arm 161 when the cap screw is tightened.

Referring now to Figure 1, the invention is shown as embodied in a filling and capping machine of the rotary type in which the empty bottles are fed into a filling machine, the bottles being filled as they are carried around in a circle on this machine, the filled bottles being discharged at a discharge station as indicated at 5 in Fig. 9. Caps are then applied to the bottles and the bottles are discharged to a suitable point for crating. The machine has a main frame 186 which carries a pedestal 187 upon which is mounted a rotary table 188 enclosed by a peripheral guard rail 189 which serves to retain the bottles on the table. The table rotates from right to left facing Figure 1 and carries empty bottles exemplified by a bottle 191 against a star wheel designated generally by the numeral 192 (Fig. 9). The star wheel 192 is carried on a vertical shaft (not shown) and overhangs the table 188 having on its periphery a plurality of notches 193 into which the bottles 191 are carried by rotation of the table. The star wheel rotates intermittently in a clockwise direction facing Fig. 9 and thus carries the empty bottles 191 in a step fashion to the head of bottle stools designated generally by the numeral 195 carried on a moving platform 196 of the filler, the stools being carried on arms 197 which are rotated by mechanism within a housing 198 on the frame 186 to move the stools between a position flush with the platform 196 and an elevated position as shown in Figure 1. The rotation of the star wheel and the platform are so coordinated that a bottle is moved onto successive stools as these stools pass the star wheel, movement of the bottles being stopped by a ring 199 having fingers 201 against which the bottle abuts in its movement. The ring 199 is arranged for adjustment in its position so as to accommodate the machine for different sizes of bottles. The platform 196 moves continuously in a direction from right to left facing Figure 1, bringing successive bottles around to a discharge station as indicated in dotted lines at 5 (Fig. 9). During this rotation the stools 195 are raised,

causing the mouth of the bottles to engage with filler valves 202 which act to fill the bottle with milk from a tank 203. The stools 195 are dropped to a position flush with the platform 196 as they approach the discharge station 5. As the stools move past the discharge station, they pass under the star wheel 192 moving the bottle thereon into the discharge station 5 and into one of the recesses 193 of the star wheel, whereby upon rotation of the star wheel to bring an empty bottle onto the stools, a filled bottle is removed from the bottle discharge station to a bottle capping station as indicated at 6 (Fig. 9), the bottle remaining stationary at this station until the next movement of the star wheel, during which period the cap is seated on the bottle by reciprocation of the crosshead 18 as heretofore described. The next succeeding movement of the star wheel brings the capped bottle back onto the table 188, whereby rotation of the table withdraws the bottle from the recess 193 of the star wheel, thus completing the filling and capping operation.

The capping mechanism is so positioned as to conduct the various operations incident to the capping, subsequent to the time the bottle leaves the discharge station 5 and, prior to the time it is delivered onto the table 188. This mechanism is in this instance carried on the pair of spaced upright rods 12 and 13, heretofore described, attached to the frame 186 through sleeves 204 and 205 and extending upwardly along the edge of a capping plate 206 (Fig. 9) which serves to support the bottles between the platform 196 and the table 188. A guide bar 207 extends along the front of the plate 206 to retain the bottles in the star wheel and is adjustable by means of a crank 208 for different sizes of bottles. An arm 209 (Fig. 1) is likewise adjusted by the crank 208 to adjust the position of the guard rail 189 (Fig. 1).

Means are provided for applying the hood 186 to the head of a bottle as it moves forward from the discharge position 5 to the capping position 6, this mechanism including a hood magazine 211 adjustably carried on a rod 212 attached to a hood chute indicated generally by the numeral 213 which is in turn attached to a bracket 214 secured to the upright 155, as described and claimed in my copending application Serial No. 402,517, filed July 15, 1941, entitled "Bottle cap applying device." The magazine 211 carries a stack of hoods as indicated at 215 retained in the magazine by fingers 216. The chute 213 has spaced side members 217 adapted to receive the hood members one at a time as they are withdrawn from the magazine, the hood members rolling down the chute into the position shown in Fig. 9 so as to be disposed in the path of the head of a bottle passing thereunder, the hoods being slid out of the chute by forward movement of the bottle and whipped onto the head of the bottle by means of a flexible chain 218 disposed to cross the mouth of the chute. The hoods are withdrawn one at a time from the magazine by means of a suction cup 219 carried on the end of a piston 221 actuated by a lever 222 which is in turn rotated by an arm 223 driven from a shaft 224 carried in a bracket 225 likewise attached to the upright 155. The shaft 224 is driven from a wheel 226 disposed in the path of a bottle carried on the stools 195 in such position as to be engaged by the neck of the bottles while clamped in the filler between the filler valve 202 and the stool 195, the forward movement of the table 196 moving the

wheel 226 outwardly, thus rotating an arm 227 clutched to the shaft 224 by means of a friction clutch 228 spring pressed into position by a spring 229. The wheel 226 and arm 227 are urged into the path of the bottle by a tension spring 231 and the bottle rotates the wheel and arm against the tension of this spring, the clutch 228 providing overtravel to accommodate for different sizes of bottles, as described in my said copending application. Connected to the plunger 221 through a valve member 232 is a vacuum hose 233 connected to a depending pipe 234 in turn attached to vacuum pump mechanism of conventional design carried in a housing 235 beneath the frame 186, the valve 232 acting to apply reduced pressure to the suction cup 219 when the same is advanced toward the magazine and to permit the increase of pressure therein to atmospheric as the suction cup returns to the position shown in Figure 1 to thereby deposit the hoods into the chute.

The capping head is reciprocated through its cap seating stroke, as heretofore described, by the operating rod 23, which rod is threaded at its lower end as shown at 236 and is received in the threaded bore of an end piece 237. The lower end of the end piece is pivotally connected to a crank arm 238 fixed to a shaft 239 carried in a gear casing 241, which also carries a pulley 242 driven from a motor 243, the gearing within the casing being such as to drive the pulley 242 in a counterclockwise direction so as to actuate the crank arm 238 through a capping stroke. The pulley 242 carries handles 244 for manual movement of the capping head during adjustment of the device. The gearing in the casing 241 also serves to drive the platform 196 and the star wheel 192, these elements being driven in timed relation to effect reciprocation of the crosshead while the star wheel and the bottle occupy a stationary position on the plate 206. The arm and shaft are returned by a spring 245 acting between the frame and a crank arm 246. It will be seen that through this mechanism the operating rod is given a vertical reciprocating motion, the amplitude being such as is required by the capping operation. It will be seen that the elevation of the cross-head must be varied with the size of the bottles to which the cap is being seated, and consequently the effective length of the rod 23 must be varied. For this purpose the crank 30 is provided on the upper end of the rod 23 as heretofore described so that the threaded lower end 236 may be screwed into or out of the end piece 208 to adjust the effective length of the rod. To facilitate this adjustment the operating rod carries a plurality of markings cooperating with the end of a rod 247 to indicate the position of the cap seating mechanism, that is, to indicate the size of bottle for which the capping mechanism is set.

It will be seen that the elevation of the hood applying mechanism including the magazine and chute must also be adjusted for different heights of bottles, and for this purpose I have arranged to support the bottle wheel 226 and associated mechanism, the hood magazine 211, the hood selector mechanism, the hood chute, and the bottle centering mechanism on the frame comprising the cross-bar 17 and upright 155. Therefore, by adjusting the position of this frame, each of these elements may be simultaneously adjusted to the position required for different standard sized bottles. In order to bring about this adjustment, I provide a yoke designated generally by the numeral 248 pinned to the uprights 12 and 13 and

depending flanges 249 between which is supported a transverse shaft 251 carrying a crank 252 and a bevel gear 253. The gear 253 meshes with a quarter turn gear 254 carried on a screw 255 having bearing support in the yoke and retained in position by a collar 256, the screw projecting upwardly and having threaded engagement in a threaded boss 257 attached to the cross-bar 17 whereby upon rotation of the crank 252, the bar 17 and the associated frame mechanism is raised and lowered. The rod 247 is attached to the top of the yoke 248 and bears suitable indicia indicating the position of the bar 17 for the different sizes of bottles. It will be seen that by this means all the above-mentioned mechanisms are simultaneously adjusted to uniform positions in response to rotation of the cranks 252 and 30 and the relative positions of the hood applying means and the cap seating means are indicated, and consequently the operator is assured of proper coordination between these various elements.

In Figs. 11 and 12 I have shown a modified form of the diaphragm portion of the device, the remainder being identical with that heretofore described. In this form of the invention a depending flange 261 is provided attached to the head support and analogous to the depending flange 66 of the form heretofore described, the flange 261 being externally threaded as shown at 262. Within the supporting member is a central opening 263 communicating with the plunger chamber and in effect forming a part thereof, the walls of said opening converging slightly to positively prevent the disk 68 from dropping through the opening until pressed through by action of the plunger 38. Surrounding the opening 263 is a diaphragm seat indicated generally by the numeral 264 against which a ring or flange portion 265 of a rubber or similar flexible diaphragm 266 is seated. The flange portion 265 is held against the seat 264 by an upper clamping and spacer ring 267, the outer periphery of which seats snugly against the inner wall of the flange 261. The diaphragm has a cup-like intermediate wall 268 having a reverse bend as shown at 269 terminating in an annular flange 271. The flange 271 is clamped against the spacing ring 267 by a clamping ring 272 which has an upwardly disposed conical flange or rib 273 received within the portion of reverse bend, whereby to clamp the lower edge of the diaphragm and to firmly seat it in position. The spacer ring and the clamping ring are compressed against the flanges of the diaphragm by means of a screw threaded cap 274 having an inwardly disposed rim 275 engaging against the clamping ring. The clamping ring has a shoulder 276 projecting inwardly for partial support of the diaphragm when inflated and should come as close as conveniently possible to the outer surface of the bottle to lend maximum support to the diaphragm in this area. The purpose of the reverse bend and the rib 273 is to cause the wall 268 to be stretched transversely of its length at the same time that it is being contracted inwardly, this stretching operation in one direction acting to shrink the wall portion in the circumferential direction, thus preventing formation of ripples or wrinkles in the wall 268 as it moves toward the surface of the bottle. Air is supplied to the space behind the diaphragm by way of a pipe 277 connected to the air valve and corresponding to the pipe 132 shown in Fig. 5. As shown in Fig. 12, when air is admitted behind the diaphragm, the wall 268 is moved outwardly into contact with the outer surface of the bottle, the wall being stretched in portions and shrunk in other portions

as indicated in this figure for the purpose of compressing the skirt against the outer surface of the bottle. During this operation the diaphragm tends to seat against the shoulder 276 as shown in Fig. 12, the shoulder acting to support the diaphragm in this area.

It will be seen that the skirt contracting mechanism is so constructed that by unscrewing the cap 274, the diaphragm and the two rings can be quickly withdrawn from the flange for quick replacement of the diaphragm in case it should be cut by broken bottles or for any other reason may need replacement. Likewise it may be easily removed for cleaning operations without dismantling the entire cap seating mechanism.

I desire to direct particular attention to the fact that the capping device can be used in its entirety and with out any structural change for applying either skirted hood caps or the conventional disk or plug-type caps simply by interrupting the supply of air to the diaphragm and by interrupting the source of reduced pressure to the suction cup 219, either of which may be accomplished in the well known manner by the actuation of a valve or the deenergization of an air compressor and vacuum pump. This is of particular importance since in ordinary practice it is necessary for a dairy to change from hood caps to plug-type caps from four to ten times per day, the capping run of each commodity conveniently being separated into bottles to which hood caps are applied and other bottles to which only plug-type caps are applied. This represents a saving in a duplication of equipment, time required in making the change, space required for the utilization of duplicate equipment, and the cost of maintaining and cleaning the extra equipment.

Operation

The empty sterile bottles are placed on the table 188 and through rotation thereof come into contact with the star wheel which transfers the bottles to the stools 195. The bottles move around on these stools and are raised into engagement with the filler valves 202 by raising of the stools into the position shown in Figure 1. While in this raised position and clamped between the valves and the stools, the bottles engage the wheel 226 just prior to leaving the stools and passing under the capping plate. Movement of the wheel 226 causes a hood to be selected from the magazine 211 dropped into the chute and transferred to a point to be engaged by the identical bottle as it moves into capping position. When the bottle carrying the hood comes to rest beneath the cap seating mechanism as shown in Fig. 2, the rod 23 is moved downward, bringing the crosshead 18 down. As the crosshead moves down the cam face 178 releases the roller 177 allowing the arms 165 and 166 to rotate under the action of the spring 173 to grasp the neck of the bottle, centering the same under the plunger 38 and bringing it into proper capping position with respect to the plunger and the diaphragm. With continued movement the skirt contracting means, including the diaphragm 72, comes into contact with the hood at the rim of the bottle. As the crosshead continues to move downward, the skirt contracting means slides upwardly on the rod 37 with the diaphragm lightly contacting the rim of the hood, the major portion of the weight thereof being taken by the counterbalancing spring 88. This relative upward movement of the skirt contracting means eventually causes the plunger to be projected into the mouth of the

bottle, forcing the disk 68 out of the chamber 51 and causing the same to be seated on top of the mouth-spanning portion 93 of the hood and against the cap seat. At this point the collar 43 comes into engagement, and continued downward movement of the crosshead causes compression of the spring 41 in an overtravel movement. During this overtravel movement the plungers 144 and 145 actuate the air valve, admitting air to the space behind the diaphragm to cause the same to move inwardly to compress the skirt portion of the hood around the bead of the bottle, the skirt folding on the pre-formed folded lines therein. The skirt of the hood is so pleated as to have slightly more stock between the folds than will be required to fit over the largest bead which will be encountered in the type of bottle for which it is made, and this excess material will be gathered between the folded lines in the form of small ribs which serve to stiffen the metal around the lower edge of the skirt.

Upon reaching the end of this overtravel movement, the crosshead 18 immediately returns to its upper position, during which movement the spring 41 expands, allowing relative movement between the crosshead and the plunger 38 and skirt contracting means, as a result of which movement the plungers 144 and 145 release the stems 123 and 128 as indicated in Fig. 8, thus exhausting the air from behind the diaphragm and permitting it to return to the position shown in Fig. 4. As the crosshead continues its upward movement, the plunger is withdrawn from the mouth of the bottle and thereafter the skirt contracting means is pulled upward by action of the pin 63 engaging the end of the slot 62 in the disk feeding mechanism to lift the skirt contracting means away from the bottle and to the elevated position. During this lifting operation the shuttle 56 is moved to feed a disk into the position shown in Fig. 3 by the weight of the skirt contracting mechanism and also by action of the rod 152 and spring 157, thus completing the cap seating operation. Shortly thereafter the bottle 85 is shifted out of its cap seating position and a new bottle having a hood thereon is substituted and the cap seating operation is repeated.

Where I use the term "reverse bend" or "reverse curve" I mean a structure in which the material of the diaphragm extends outwardly and upwardly and then reverses upon itself and extends outwardly and downwardly as shown in Figs. 11 and 12, the term referring to the cross-sectional shape of the lower portion of the diaphragm.

While I have thus described and illustrated a specific embodiment of the invention, this has been by way of illustration and not limitation, and I do not wish to be limited except as required by the scope of the appended claims, in which—

I claim:

1. The combination in a capper for seating a cap on a milk bottle having a skirted hood loosely carried over the mouth of the bottle in alignment therewith of skirt contracting means, a plunger for forcing a disk positioned therebelow into the mouth of the bottle, supporting means for carrying said skirt contracting means and said plunger, means for imparting relative approach movement between said bottle and said support to bring said skirt contracting means into operative relation with said bottle, a lost motion connection between said skirt contracting means and said plunger for forcing the disk into the bottle upon further approach movement, a second

lost motion connection between said plunger and said supporting means for further approach movement between said bottle and said support, and means responsive to the last mentioned approach movement for actuating said skirt contracting means to contract the skirt of the hood about the head of the bottle.

2. The combination in a capper for seating a cap on a milk bottle having a skirted hood loosely carried over the mouth of the bottle in alignment therewith of skirt contracting means, a plunger for forcing a disk into the mouth of the bottle over said hood, a disk magazine, means for feeding a disk from said magazine into capping position under said plunger, supporting means for carrying said skirt contracting means, and said plunger, means for imparting relative approach movement between said bottle and said support to bring the skirt contracting means into operative relation with the bottle, a lost motion connection between said skirt contracting means and said plunger for forcing the disk into the bottle upon further approach movement, a second lost motion connection between said plunger and said supporting means for further approach movement between said bottle and said support, means responsive to the last mentioned approach movement for actuating said skirt contracting means to contract the skirt of the hood about the head of the bottle, and means for actuating said disk feeding means in response to return movement between said support and said bottle.

3. The combination recited in claim 1 wherein means is provided for counterbalancing the weight of said skirt contracting means to remove most of the weight of said skirt contracting means from the bottle while the disk is being inserted into the bottle.

4. The combination in a bottle capper for applying skirted hood caps to milk bottles of supporting means, fluid operated skirt contracting means on said supporting means for contracting the skirt of a hood positioned on the head of a bottle positioned therebeneath, a plunger in said supporting means for seating a disk in the mouth of said bottle on top of said hood, means for imparting relative approach movement first between the bottle and said contracting means and plunger to bring the contracting means against the rim of the bottle with the hood therebetween and thereafter impart approach movement between said plunger and said bottle to seat the disk, overtravel means between said support means and said contracting means and plunger, and means for actuating said skirt contracting means in response to said overtravel movement to contract the skirt around the head of the bottle.

5. The combination recited in claim 4 wherein the means for actuating said skirt contracting means comprises valve means carried on the skirt contracting means on said support means, and means positioned to operate said valve means in response to said overtravel movement.

6. The combination in a capper for seating skirted hood caps on milk bottles, of skirt contracting means comprising a supporting member having relative movement toward and away from a bottle disposed therebeneath to effect a capping operation, an elastic diaphragm having a rim portion shaped to seat against the rim of the bottle with the cap therebetween, an upper peripheral fastening portion adjacent said rim portion adapted to seat against said supporting member, a depending wall portion sloping outwardly and downwardly from said rim portion in

spaced relation to the neck of the bottle for the reception of the skirt of a cap therebetween, and an outwardly disposed lower peripheral fastening portion at the lower edge of said wall portion, a spacer disposed between said upper and lower fastening portions to confine said fastening portions and forming with said diaphragm a fluid chamber extending around said depending wall portion for the reception of fluid to displace said wall portion against the neck of the bottle to press the skirt thereagainst, a clamping ring disposed below said lower peripheral fastening portion, said diaphragm and said clamping ring being shaped to stretch the diaphragm longitudinally of the bottle while the same is being contracted circumferentially thereof, and releasable means acting between supporting member and said clamping ring for compressing said spacing ring and said fastening portions between said member and said clamping ring to seal said chamber, said releasable means being the sole means for securing said diaphragm, said spacer, and said clamping ring in assembled relation on said supporting member, whereby assembly and disassembly of the parts for repair and replacement of said diaphragm is effected by release of said releasable means.

7. The combination in a capper for seating skirted hood caps on bottles of skirt contracting means comprising a supporting member movable toward and away from a bottle disposed therebeneath having the central opening for the passage of a capping plunger, a rubber diaphragm comprising a rim portion around said opening shaped to seat against the rim of the bottle, an upper flange outwardly disposed from said rim portion adapted to seat against said member to support the diaphragm thereon, a depending wall sloping outwardly and downwardly from said rim portion in spaced relation to the neck of the bottle for the reception of the skirt of a cap therebetween, said wall terminating in an outwardly and upwardly disposed annular wall, and an annular outwardly disposed lower flange on said upwardly disposed wall, a spacer ring disposed between said flanges, means for confining said flanges against the spacer ring and said supporting member to provide a substantially air tight chamber around said diaphragm, and means for applying fluid pressure to the outer side of said diaphragm to contract said depending wall against the bottle and compress the skirt thereagainst throughout the width of the skirt.

8. The combination in a capper for seating skirted hood caps on bottles of skirt contracting means comprising an inverted cup-shaped frame having a top and an annular depending flange, a rubber diaphragm having a rim portion shaped to abut at its upper side against said top and to seat at its lower side against the rim of a bottle, a depending conical wall sloping outwardly from said rim portion away from the neck of the bottle terminating in an outwardly disposed reverse curve, a ring between said flange and said diaphragm for sealing said rim against said top, a second ring for sealing the lower edge of said diaphragm against said first mentioned ring, said second ring having a rib interfitting with the reverse curve of said diaphragm, a cap detachably connected to said flange for compressing said rim, said edge and said rings against said top, and means for admitting and releasing fluid pressure between said first mentioned ring and said diaphragm to periodically contract the latter against the bottle to compress said skirt there-

against, said rib acting on said diaphragm to stretch the same longitudinally of the bottle under action of said fluid pressure while the diaphragm is being contracted circumferentially thereby.

9. The combination recited in claim 11 wherein in said spacer ring has a channel communicating with said chamber and said member has an opening registering therewith and in which annular recesses are provided around said channel and said opening at the junction thereof, and a gasket seated in said recesses for sealing the junction between said channel and said opening, one of said recesses being arranged to retain said gasket when the member and the ring are separated.

10. The combination in a capper for seating skirted hood caps on milk bottles of skirt contracting means comprising a molded rubber diaphragm having, in unstressed condition, a rim portion shaped to seat against the rim of a bottle, a depending wall sloping outwardly from said rim portion away from the neck of the bottle terminating in an outwardly disposed reverse curve portion, means for supporting said diaphragm around the head of a bottle having a skirted hood cap, and means for applying fluid pressure to the outer side of said diaphragm to contract the same against the bottle to compress said skirt thereagainst, said supporting means having shape characteristics upon which said reverse curve portion operates to stretch said diaphragm longitudinally of the bottle while the diaphragm is being contracted circumferentially thereof.

11. The combination recited in claim 10 wherein a rigidly positioned rib is seated in the outer loop of said reverse curve to stretch said wall downward under said fluid pressure while the diaphragm is being contracted thereunder, and a supporting ledge projects inward in downwardly spaced relationship to the inner loop of said reverse curve to support said wall when stretched downward under said fluid pressure.

12. A diaphragm for use in bottle capping machines for applying hood caps comprising a one-piece body of elastic material having, in normal unstressed condition, a tubular wall for the reception of the head of a bottle, said wall converging inwardly at one end to seat against the rim of a bottle, an outwardly disposed annular attachment flange adjacent the other end thereof, and means comprising shape characteristics of the material disposed between said attachment flange and said other end acting on said wall adjacent said other end to cause said wall to stretch longitudinally of the bottle to absorb excess wall material caused by contraction of said wall circumferentially around the neck of the bottle in response to the application of fluid pressure to the outer side of said wall.

13. The combination recited in claim 12 wherein in said means comprises a plurality of ribs spaced annularly of said wall in the junction between said flange and said other end of said wall on the side thereof opposite the bottle and which further acts to reinforce the diaphragm.

14. A diaphragm for use in bottle capping machines comprising a one-piece molded body of rubber having a coplanar flange for attachment to capping machines provided with a central opening, a conical wall depending from said opening provided intermediate its edges with an out-

wardly disposed bend terminating in an outwardly disposed attachment flange, each of said flanges having raised ribs on opposite sides thereof intermediate the edges of the flanges shaped for reception in complementary grooves of supporting means to prevent dislocation of the flanges through stretching thereof.

15. The combination in a capper for seating skirted hood caps on bottles of skirt contracting means comprising a supporting member movable toward and away from a bottle disposed therebeneath having a central opening for the passage of a capping plunger, a rubber diaphragm comprising a rim portion around said opening shaped to seat against the rim of the bottle, an upper flange outwardly disposed from said rim portion adapted to seat against said member to support the diaphragm thereon, a depending wall sloping outwardly and downwardly from said rim portion in spaced relation to the neck of the bottle for the reception of the skirt of a cap therebetween, said wall terminating in an outwardly and upwardly disposed annular wall, and an annular outwardly disposed lower flange on said upwardly disposed wall, spacing means disposed between said flanges for confining the upper flange against said support member and for closing the space between said flanges to provide a substantially air tight chamber around said diaphragm, and a ledge projecting inwardly toward the bottle below said lower flange, said diaphragm having a plurality of circumferentially spaced ribs on the side thereof away from the bottle and at the junction between said wall and said lower flange to span the space between the neck of the bottle and said ledge when the diaphragm is contracted against the bottle to prevent rupture of said diaphragm when capping undersized bottles.

16. The combination in a capper for seating a cap of the type having a skirted hood and a disk seated thereon on a milk bottle, of skirt contracting means having a central opening, a plunger movable through said central opening for forcing a disk and a central portion of said hood into the mouth of the bottle, supporting means for carrying said skirt contracting means and said plunger, means for imparting relative approach movement between said bottle and said support to bring said skirt contracting means into operative position against the head of the bottle with said hood disposed therebetween, said plunger having lost motion with respect to said skirt contracting means for further approach movement of the plunger to force said cap and a central portion of the head into the mouth of the bottle, said skirt contracting means comprising a rubber diaphragm, including a vertically disposed tubular wall for the reception of the head of the bottle therein, with said hood disposed thereon, said wall curving inwardly adjacent its upper edge to seat against the rim of the bottle, a layer of fabric seated in the surface of said wall in said inwardly curved area to facilitate sliding movement of the hood with respect to the bottle and said wall upon said further approach movement of the plunger, and means for applying fluid pressure to the exterior of said diaphragm to contract said wall against the neck of the bottle and compress the skirt thereagainst.

CERTIFICATE OF CORRECTION.

Patent No. 2,349,524.

May 23, 1944.

RUDOLPH SONNENBERG.

It is hereby certified that error appears in the printed specification of the above numbered patent requiring correction as follows: Page 8, first column, lines 61 and 62, claim 5, strike out the comma and words ", and means" and insert the same before "on", line 61, same claim; page 9, first column, line 6, claim 9, for the claim reference numeral "11" read --6--; and that the said Letters Patent should be read with this correction therein that the same may conform to the record of the case in the Patent Office.

Signed and sealed this 25th day of July, A. D. 1944.

Leslie Frazer

(Seal)

Acting Commissioner of Patents.
